Primary Examiner—Dominic Simone
Attorney, Agent, or Firm—Banner & Allegretti, Ltd.[57] **CLAIM**

The ornamental design for a side element of a shoe upper, as shown and described.

DESCRIPTION

FIG. 1 is a side elevational view of one side of a shoe upper having a side element showing my new design;

FIG. 2 is a front elevational view of the shoe upper having the side element shown in FIG. 1; and,

FIG. 3 is a top plan view of the shoe upper having the side element shown in FIG. 1.

The broken line showing of a shoe sole and the remainder of the shoe upper is for illustrative purposes and forms no part of the claimed design.
